UNITED STATES PATENT OFFICE

141,065

DESIGN FOR AN ELECTRODE HOLDER OR SIMILAR ARTICLE

Alexander Gilmour, Terre Haute, Ind.

Application January 29, 1945, Serial No. 117,668

Term of patent 14 years

(Cl. D26—1)

To all whom it may concern:

Be it known that I, Alexander Gilmour, a citizen of the United States, residing at Terre Haute, in the county of Vigo and State of Indiana, have invented a new, original, and ornamental Design for an Electrode Holder or Similar Article, of which the following is a specification, reference being had to the accompanying drawing, forming part thereof.

Figure 1 is a side elevational view of an electrode holder, or similar article, showing my new design,

Figure 2 is a top plan view, and

Figure 3 is a bottom plan view thereof.

I claim:

The ornamental design for an electrode holder or similar article, as shown.

ALEXANDER GILMOUR.
